METAL WEATHER STRIPPING

Harry A. Kammerer, Mount Vernon, N. Y.

Application December 21, 1935, Serial No. 55,635

1 Claim. (Cl. 20—69)

This invention relates to metal weatherstripping and more particularly to such weatherstripping adapted for use with sliding sash windows of that type in which no weights are employed, 5 the sash being held at different elevations by a friction device, one element of which is carried by the sash and the other by the window frame, and both members being operatively connected at all times in such manner that one of the elements 10 of the friction device has a frictional sliding union with the other element.

Such friction sliding sash balances are usually set within a recess or groove formed in the vertical edges of the sash and this leaves very little 15 surface at the edges of the sash for carrying the usual form of weatherstripping.

One object of the present invention therefore is to provide weatherstripping comprising two interlocking members, one carried by the sash and 20 the other fitted to the sash guide of the window frame, and to so construct such weatherstripping that the sash member will provide a metallic lined recess open at the front within which the sash balance may be fitted for entire freedom of action, 25 and at the same time so construct the member of the weatherstripping carried by the sash as to insure its permanent installation and an effective sliding air-excluding coupling with the complementary member positioned within the sash 30 guide of the window frame. A further object is to so form both members of the weatherstripping that they shall be secured in place by fastenings extending along a central longitudinal line, thus leaving the lateral edges of both members free, 35 permitting a limited lateral yielding to the movement of the sash without breaking the air-excluding coupling.

The present invention is shown in the accompanying drawing in which—

40 Fig. 1 shows a broken horizontal sectional view through the sash and frame of a window equipped with the improved weatherstripping;

Fig. 2 shows in perspective the frame member of a section of such weatherstripping;

45 Fig. 3 shows in perspective a portion of the sash member.

Similar reference characters will be employed throughout the specification and drawing to designate corresponding parts.

50 In the drawing 1 indicates the side members of a sliding sash and 2 represents portions of the sides of a window frame provided with the usual vertically extending guides 3 into which the side edges of the sash are fitted for vertical sliding movement. Except as hereinafter pointed out,

the window frame and the sash, insofar as the sliding mounting of the sash in the frame is concerned, may be of any usual or ordinary construction.

In the present instance the sash 1 is provided with longitudinally extending centrally disposed grooves 4 at each edge within which the friction balance device 5 operates. The friction balance device shown is of that type comprising a member 6, one end of which is permanently connected 10 to the window frame and a member 7 connected at one end permanently to the sash 1, the members 6 and 7 having a frictional sliding connection with each other in a manner well known to those skilled in this art. In and of itself the friction 15 balance device constitutes no part of the present invention.

My improved weatherstripping in its preferred form constitutes a window frame member 8 made of some suitable sheet metal and of a width to fit 20 within the guides 3 of the window frame, and of a length approximately that of the vertical height of the window sash. Preferably the member 8 will be depressed and flattened along its longitudinal medial line, as indicated at 9, thus bringing the lateral edges 10 into a slightly different plane than the flattened portion 9. The free 25 edges of the member 8 are bent over forming overlapping flanges 11 arranged parallel to the outer face of the edges 10 and spaced from the body portion, and are bent outwardly to form the overlapping flanges 12 forming the grooves or slots 13. The frame member is provided with centrally disposed openings 14 through which the attaching 30 screws 15 may be passed to hold it in position 35 in the guideways 3.

Cooperating with the frame members are sash members 16, one being shown in perspective in Fig. 3 of the drawing. The sash members 16 are provided with a longitudinally extending forward 40 projecting portion 17 of a size and shape to fit the grooves or seats 4 in the edges of the sash 1 and along each lateral edge 18 fits against the free edge of the sash as indicated, thence are bent 45 inwardly parallel to edges 18 to form the flanges 19 enclosing the slide groove 20. The sash member 16 is provided with holes 21 to receive the attaching screws 22. When the sash members are applied, as shown in the drawing, the bowed projection 17 fits within the grooves 4 of the sash 50 member and the flanges 19 slidably engage with the interlocking flanges 12 of the frame member 8, providing a permanent sliding connection, and when employed as shown, excluding the entrance 55 of air at the sides of the sash.

It will be observed that the lateral bearing surfaces 18 of the sash member 16 overlap the outer edges of the sash member at each side of the groove 4 which receives the projecting portion 17 5 and is permanently secured thereto to move with the sash while maintaining the interlocking connection therewith.

It will be further noted that the offsetting of the 10 sliding connection between the members with relation to the plane of the central part 9 of the frame member 8 provides a yielding or spring connection which will be maintained even though a slight lateral displacement of the sash with relation to the window frame may take place 15 during the raising and lowering of the sash, thus retaining the weather-tight connection of the sash and frame at all times.

In applying the sash to the frame the sash member 16 is first connected to the edges of the 20 sash by the screws 22. The members 8 and 16 are then connected with each other by interlocking the flanges 12 and 19 as indicated in Fig. 1. As thus connected the sash and the weatherstripping are inserted in the guides 3 of the 25 window frame. The sash is then elevated slightly and the frame member 8 is drawn down until its lower end rests upon the window sill. An attaching screw 15 is inserted in the lowermost opening of the frame member whereupon the sash 30 may be elevated to the full extent required, thus uncovering other openings 14 therein to receive other attaching screws 15. Of course it will be understood that the strip 22 forming part of the window frame is removable and held in place by 35 attaching screws 23, all to facilitate the adjustment of the sash and weatherstripping in the guides 3 of the window frame.

The assemblage of the weatherstrip members and the sash preliminarily to fitting into the sash 40 guides of the window frame is greatly facilitated by the fact that the interlocking flanges between the frame member and the sash member of the weatherstripping are arranged parallel to the plane of such members or the portions thereof 45 which bear against the side edges of the sash and

the back of the guides of the window frame. This construction insures that the two members of the weatherstripping will be held in coupled engagement while inserting the sash carrying such members in the window frame. It will be further 5 noted that as the interlocking flanges of the frame member of the weatherstripping are slightly offset with relation to the plane of the intermediate part which is secured to the back of the sash guide, there is a yielding or spring action of the 10 lateral edges of the frame member tending to hold the parallel interlocking flanges coupling the weatherstrip members together always in coupled position and permitting a limited lateral movement of the sash member of the window without 15 any liability of affecting the air excluding function thereof.

I claim:

Weatherstripping for sliding sash windows comprising a sheet metal frame member of a 20 width corresponding to the width of the sash guide of the window frame and provided with a longitudinally extending medial flat attaching portion with the lateral edges in a different plane with relation to the flat attaching portion and 25 provided along its marginal edges with inwardly and outwardly extending overlapping flanges spaced from and substantially parallel to the face of the body portion and to each other, and a sheet metal sash member having a longitudinally extending centrally disposed projection to fit the groove in the edge of the sash having an attaching portion along its longitudinal medial line only and provided with laterally extending flanges 30 adapted to fit against the edges of the sash at 35 each side of the groove and provided with an inwardly extending coupling flange along each edge and parallel thereto interlocking with and forming a permanent sliding connection with the overlapping flanges of the frame member, said 40 centrally disposed projection forming a lining for the groove or recess in the edge of the sash and an open chamber to receive the sash balance.

HARRY A. KAMMERER. 45
